CYLINDER HEAD CONSTRUCTION FOR
DIESEL ENGINESWilliam Hope Ross, Estevan, Saskatchewan,
Canada

Application February 9, 1937, Serial No. 124,881

1 Claim. (Cl. 123—173)

This invention relates to a cylinder head construction for Diesel engines and more particularly to an improved construction which is designed to provide a head which will have a longer life and require less space and operate more efficiently than the heads ordinarily provided.

Engine heads for Diesel engines of known design have had the water jacket and the head cast in one piece. Others have the head formed in two parts with the cooling chamber constituted by the space between those parts. It has been common practice in the construction of those heads to use sand cores in forming at least a portion of the cooling chambers. In fact the design has in many cases been such that the use of cores could not be avoided. The use of cores caused pitting of the metal and necessarily resulted in parts of unequal cross-section. It also provided surfaces which were inaccessible and could not be machined.

Due to the combination of these effects the cast parts were unduly subject to crystallization and cracking. The unequal expansion and contraction due to uneven thickness of the parts as well as the faults in the metal due to the method of forming the parts caused premature failure of the cylinder heads.

Furthermore, the inaccessibility of the surfaces, especially the cooling surfaces, made it impossible to clean these parts except by the use of acids and equivalent chemicals. Such cleaning is necessary because of the high temperatures of Diesel engines and the necessity of removing excess heat. Scale had to be removed. The chemicals further abetted the crystallization and when the parts so cleaned bore a substantial proportion of the stresses the result was premature failure of the parts. To overcome this the size of the cylinder head was increased. This produced obviously disadvantageous features.

It is the object of the present invention to increase the efficiency of a Diesel engine and at the same time reduce the size and weight of its head without impairing its strength.

It is a further object of this invention to produce a head of such a design that the parts can be made of substantially equal thickness and thus eliminate the stresses and strains caused by uneven expansion and contraction. It is a further object of the invention to provide a head member which eliminates dead air pockets and thus increases the efficiency of the engine.

It is a further object of the invention to provide a head which has a removable water jacket and from which the scale can be easily and effi-

ciently removed without boiling with injurious chemicals or removing the entire head.

It is also an object of the invention to provide a Diesel head construction which materially reduces both the weight of the engine and the head room required.

Another object of the invention is to provide a head construction in which all the forces are applied directly so that each part resists as large a force as possible per unit of weight. In this way weight is reduced to a minimum.

These objects are attained by making the head portion, that is both head proper and water jacket, in two pieces. The head proper is the heavier part, is conical and formed with a flange 15 at its base. The flange is bolted to the cylinder walls and both the flange and the head proper are cast forged or otherwise formed in single piece, the cross-sectional thickness of which is substantially uniform.

The water jacket rests upon and fits snugly about the head. It is attached to the head by means which are independent of those holding the head proper to the cylinder. The jacket can be removed and the cooling surfaces exposed for cleaning without detaching the complete head. Such easy cleaning promotes frequent cleaning and lengthens the life of the head.

The invention is further illustrated by reference to the drawing which shows a cylinder head construction embodying the features which form the subject matter of this application.

Figure 1 is a perspective view of the assembly with the cover detached and somewhat removed from the head.

Figure 2 is a section taken in a vertical plane passing through a diameter of the head, and

Figure 3 is a top plan view with the cover partially cut away.

In the drawing the head 1 has a flange 2 at 40 the base of a central cone. This flange completely encircles the base and rests upon the cylinder wall 3. The top inner edge of the cylinder wall is slightly cut away to form a seat 4 for the shoulderlike projection 5 on the bottom 45 of the annular flange. At the apex of the cone of the head an opening 6 for a fuel injection valve is provided. There is no special cooling arrangement required for this particular part of the head. The injection valve is in contact with the head 50 for only a small part of its length. The surface available for heat transfer is thus reduced and the temperature remains low. It has been found that when the length of the opening with which the fuel injection valve is in contact is not more 55

than three inches the temperature of the valve is such that it is not necessary to provide a cooling arrangement other than that ordinarily provided for the head proper.

5 Extending vertically through the flange and equally spaced about the circumference there is a plurality of holes 7. Every alternate hole registers with a similar hole 8 in the upper surface of the cylinder wall. These latter communicate 10 with the water jacket 9 which cools the cylinder walls. The remaining holes in the depending flanges are adapted to receive studs 10 which project from the upper surface of the cylinder wall. These studs are threaded and nuts 11 hold 15 the head in place on the cylinder.

15 A horizontal opening 8a in the flange provides a passage for introducing starting air into the cylinder. Circular gaskets 12 surround the lower opening of the holes 7 and provide an effective 20 seal between the water jacket and the cylinder. The cover 13 fits over the head 1 and the lower edge of its side wall 14 rests upon the upper outer edge of the annular flange 2.

The apex of the conical top of the cylinder 25 head projects and snugly fits into the aperture 14a provided in the top of the cover. An annular washer 15 bolted by means of studs and nuts 16 connects and seals the joint between the apex of the cone and the cover. The cover may be attached and held firmly to the annular flange by 30 means of lugs 17 welded or otherwise suitably attached to its side wall 14. Co-operating with these lugs are hooks 18, the lower end of which is designed to engage a recess 19 extending around 35 the base of the flange 2. The upper end of these attaching members is threaded to receive a nut or other tightening device by which the cover may be tightly secured to the flange and thus form in co-operation with the washer 20 a water-tight seal. The cover thus provides a space 40 connected with the cylinder water jacket and adapted to receive cooling fluid for the head. An opening fitted with a pipe 21 is provided for the circulation of the cooling fluid.

45 It will be seen that a cylinder head construction has been provided which requires a minimum

of space and which at the same time provides an efficient cooling jacket which can be easily and quickly removed without dismantling the whole engine head. It is thus possible to clean easily both the circulating system and the water jacket 5 itself and thus prevent the scaling which is occasioned both by cleaning with acids and the like and also by the lack of cleaning.

Both the core and the flange portion of the head 1 are made, according to the invention, of 10 substantially the same cross-sectional thickness, without regard to the point at which the section being considered is taken. This is clearly shown in Figure 2. Such a construction not only obviates the stresses and strains caused by uneven 15 contraction and expansion of parts having widely varying thicknesses, but it also provides an engine head, all the surfaces of which may be machined.

It will be appreciated that the head construction according to the invention is one in which the possibility of what is known as "dead air pockets" is eliminated. These "pockets" are spaces into which the mixed fuel and air current from the nozzle does not reach. Since there is no 20 circulation the mixing of fuel and air is not as intimate as elsewhere in the head and the combustion of the fuel in these spaces is incomplete. It will be seen that spaces which could act in the 25 above manner are not found in the head construction according to the invention.

What I claim as my invention is:

A cylinder head construction comprising in combination a cylinder wall, a conical head member of substantially uniform thickness having a 30 fuel injection valve opening at its apex and an integral depending annular flange at its base, abutting the upper surface of the cylinder wall, a cover fitting over said head member to form a 35 water chamber and having an opening for the apex of said head member, means for detachably securing the cover to the flange of the head member and means for detachably securing the flange to the cylinder wall.

46 WILLIAM HOPE ROSS.
